SOLAR DISTILLING APPARATUS

Charles Greeley Abbot, Washington, D. C.

Application March 15, 1937, Serial No. 131,050

5 Claims. (Cl. 202—180)

My invention is designed primarily to distill water for drinking or storage battery purposes, in regions where much sunlight is available, and water is apt to be charged with undesirable chemicals. The device may, however, be used to distill other liquids.

My device is illustrated in the accompanying drawing, wherein corresponding parts are designated by corresponding numerals.

Figure 1 shows a side elevation of the device, partly diagrammatic.

Figure 2 shows an elevation looking from the left of Figure 1, also partly diagrammatic.

Figure 3 shows, looking from the left of Figure 1, a cross-section of portions of the ray-absorptive tube and its transparent vacuum-containing sheath, on an enlarged scale as compared to Figures 1 and 2.

Figure 4 shows diagrammatically the driving mechanism of the ray-collector.

To fix ideas, liquid to be distilled is introduced into container 19, and into its inclined snout which encloses the condenser tube 18. Thus the liquid to be distilled is slightly preheated at the same time that it causes the vapor in tube 18 to condense. The slightly preheated liquid flows through tube 17 into the heating tube 13, in which the liquid is heated and vaporized by heat transmitted thereto by radiant energy from the sun concentrated by the mirror 8. The flow of the liquid through tubes 17 and 13 is automatically at such a rate as to replace liquid evaporated in tube 13 from the liquid surface at the level of the liquid in container 19.

The vapor of the liquid passes through tube 18, and is condensed by the contact of the surrounding liquid contained in the inclined snout attached to container 19. The condensate falls into the receiving vessel 21. A vacuum between the walls of tube 14 serves to hinder loss of heat from tube 13 by convection.

With this general explanation in mind I proceed to particulars.

Referring to Figures 1, 2, and 4: Roller bearings 3, 4, 5, are affixed to supports 1, 2. On these rest hollow trunnions, 6, 7, affixed to a concave parabolic cylindric mirror, 8. The trunnions, 6, 7, and the roller bearings 3, 4, 5, are so placed that the focal line of the mirror, 8, lies centrally within the trunnions 6, 7, and the mirror, 8, is free to rotate about its focal line, as about an axis parallel to the axis of the earth. A wheel, 9, with two grooves in its periphery, is affixed to the lower trunnion, 6, with some freedom of angular adjustment by means of tangent screws

10, 11. These bear on a projecting lug, 20, clamped upon the trunnion, 7. A train of clock-work, indicated diagrammatically in Figure 4, restrains the rotation which the weight, 12, tends to impart, so that the mirror rotates along with the apparent daily angular motion of the sun in the heavens at 15° per hour. After a day's run, the barrel of the clockwork may be rewound, thus setting the mirror back to its morning position. I am accustomed to make the mirror of aluminum products, employing a sheet of a highly reflecting commercial product. Said sheet may be fastened down with metallic straps to a cradle of parabolic cylindric curvature, said cradle being made up of duralumin. But I do not restrict myself to mirrors of this construction.

I prefer to use in the focus of the mirror, 8, a metal tube, 13, preferably of copper, blackened with lampblack or some other ray-absorptive-coating. The tube 13 is surrounded all through the mirror, 8, by a transparent plurally-walled tube, 14, containing a high vacuum between its walls. Easily separable joints, 15, 16, connect the blackened tube, 13, to extension tubes 17, 18, leading, respectively, into and through the container, 19. The tube, 17, may well be of rubber. The object of the joints 15, 16 is to enable the tube, 13, to be removed so as to clean out the deposit which is apt to collect within vessels used for distillation. The tube, 13, does not deliver directly into the tube 18, but into a box, 22, so that spray of liquid undistilled may not enter the tube 18.

I prefer to make the container, 19, with an enlargement at the top, and capable of holding several gallons of liquid to be distilled and with a long tube-like continuation parallel to the tube, 13, lying underneath the mirror, 8. Within this long continuation of the container, 19, the extension tube, 18, may be cooled sufficiently by the surrounding liquid to condense the vapor formed in the tube 13, and the condensate fall into the receptacle, 21. At the lower end of the container 19, it joins the extension tube, 17, so that liquid is supplied to the tube, 13, by gravity, just as fast as liquid leaves the tube, 13, by evaporation.

What I claim as my invention and desire to protect by Letters Patent is:

1. In a solar distilling apparatus, a vaporizer for a liquid to be distilled which includes a ray-concentrator for concentrating solar rays upon a linear focus and a ray-absorber-tube lying in said focus to receive concentrated solar rays from said ray-concentrator, said ray-concentrator and ray-absorber-tube being so mounted as to dispose

their axes approximately parallel to the earth's axis, and means for rotating said concentrator about said linear focus as an axis, means for supplying liquid to said vaporizer including a container for the liquid and means of communication between said container and the lower end of said ray-absorber-tube, a condensing means in heat interchanging relation with liquid in said supplying means for condensing vapor from said ray-absorber-tube, means of communication between the upper end of said ray-absorber-tube and said condensing means and extending above the level of the liquid in said container and said ray-absorber-tube whereby only vapor formed in said ray-absorber-tube may rise into said condensing means to be condensed therein, said supplying and condensing means including a portion extending adjacent to and in compact relation with said ray-concentrator, and a receptacle for condensate in communication with the outlet of said condenser tube.

2. In a solar distilling apparatus, a vaporizer for liquid to be distilled which includes a ray-concentrator comprising a parabolic mirror whose generatrices are parallel to its linear focus for concentrating solar rays upon said linear focus and a ray-absorber-tube lying in said focus to receive concentrated solar rays from said ray-concentrator, said ray-concentrator and ray-absorber-tube being so mounted as to dispose their axes approximately parallel to the earth's axis, and means for rotating said mirror about said linear focus as an axis, a container for liquid to be distilled having a downwardly projecting extension communicating with the lower end of said ray-absorber-tube, a tube in heat interchanging relation with the liquid in said container and extension for condensing vapor from said ray-absorber-tube, means of communication between the upper end of said ray-absorber-tube and said condenser tube and extending above the level of the liquid in said container and said ray-absorber-tube whereby only vapor formed in said ray-absorber-tube may rise into said condenser tube to be condensed therein, said container extension and its condenser tube extending adjacent to and in compact relation with said ray-concentrator, and a receptacle for condensate in communication with the outlet of said condenser tube.

3. In a solar distilling apparatus, a vaporizer for a liquid to be distilled which includes a ray-concentrator for concentrating solar rays upon a linear focus and a ray-absorber-tube lying in said focus to receive concentrated solar rays from said ray-concentrator, said ray-concentrator and ray-absorber-tube being so mounted as to dispose their axes approximately parallel to the earth's axis, and means for rotating said concentrator about said linear focus as an axis, means for supplying liquid to said vaporizer including a container for the liquid and means of communication between said container and the lower end of said ray-absorber-tube, condensing means in heat interchanging relation with liquid in said supplying means for condensing vapor from said ray-absorber-tube, means of communication between the upper end of said ray-absorber-tube and said condensing means and extending above the level of the liquid in said container and said ray-absorber-tube, means be-

tween the outlet of said ray-absorber-tube and the inlet to said condensing means whereby liquid is prevented from being driven over from said ray-absorber-tube into said condensing means, whereby only vapor formed in said ray-absorber-tube may rise into said condensing means to be condensed therein, said supplying and condensing means including a portion extending adjacent to and in compact relation with said ray-concentrator, compact unit, and a receptacle for condensate in communication with the outlet of said condenser tube.

4. In a solar distilling apparatus, a vaporizer for a liquid to be distilled which includes a ray-concentrator for concentrating solar rays upon a linear focus and a ray-absorber-tube lying in said focus to receive concentrated solar rays from said ray-concentrator, a transparent, vacuum-containing heat-insulating tube surrounding said ray-absorber-tube, said ray-concentrator and ray-absorber-tube being so mounted as to dispose their axes approximately parallel to the earth's axis, and means for rotating said concentrator about said linear focus as an axis, means for supplying liquid to said vaporizer including a container for the liquid and means of communication between said container and the lower end of said ray-absorber tube, condensing means in heat interchanging relation with liquid in said supplying means for condensing vapor from said ray-absorber-tube, means of communication between the upper end of said ray-absorber-tube and said condensing means and extending above the level of the liquid in said container and said ray-absorber-tube whereby only vapor formed in said ray-absorber-tube may rise into said condensing means to be condensed therein, said supplying and condensing means including a portion extending adjacent to and in compact relation with said ray-concentrator, compact unit, and a receptacle for condensate in communication with the outlet of said condenser tube.

5. In a solar distilling apparatus, a vaporizer for a liquid to be distilled which includes a ray-concentrator for concentrating solar rays upon a linear focus and a ray-absorber-tube lying in said focus to receive concentrated solar rays from said ray-concentrator and means for mounting said ray-concentrator and said ray-absorber-tube to receive solar rays, means for supplying liquid to said vaporizer including a container for the liquid and means of communication between said container and the lower end of said ray-absorber-tube, condensing means in heat interchanging relation with liquid in said supplying means for condensing vapor from said ray-absorber-tube, means of communication between the upper end of said ray-absorber-tube and said condensing means and extending above the level of the liquid in said container and said ray-absorber-tube whereby only vapor formed in said ray-absorber-tube may rise into said condensing means to be condensed therein, said supplying and condensing means including a portion extending adjacent to and in compact relation with said ray-concentrator, and a receptacle for condensate in communication with the outlet of said condenser tube.
